United States Patent Office

Des. 183,828
Patented Nov. 4, 1958

183,828

MARINE STERN HANDLE

Jack De Young, Grand Haven, Mich., assignor to Aqua
Flair Marine Equipment Company, Grand Rapids,
Mich., a corporation of Michigan

Application August 20, 1957, Serial No. 47,461

Term of patent 14 years

(Cl. D71—1)

FIG. 1

FIG. 3

Fig. 1 is a perspective view of a marine stern handle embodying my new design;

Fig. 2 is a top plan view thereof; and

Fig. 3 is a side elevational view thereof.

I claim:

The ornamental design for a marine stern handle, substantially as shown.
